(57) **CLAIM**

The ornamental design for a “table for bathtub,” as shown.

DESCRIPTION

FIG. 1 is a perspective view of a table for a bathtub showing my new design in condition of a use with a bathtub;
FIG. 2 is a front view thereof;
FIG. 3 is a rear view thereof;
FIG. 4 is a right-side view thereof;
FIG. 5 is a left-side view thereof;
FIG. 6 is a top side view thereof;
FIG. 7 is an enlarged perspective view of the table showing a truncated version of the same design of a table for bathtub;
FIG. 8 is a front view of FIG. 7;
FIG. 9 is a rear view of FIG. 7;
FIG. 10 is a right-side view of FIG. 7;
FIG. 11 is a left-side view of FIG. 7; and,
FIG. 12 is a top side view of FIG. 7.
The broken line showing a bathtub is for illustrative purposes only and forms no part of the claimed design.
